United States Patent Office

Des. 176,929
Patented Feb. 14, 1956

176,929

COFFEE MAKER OR SIMILAR ARTICLE

Paul O. Rawson, Jr., Trumbull, and Walter E. Moore,
Stratford, Conn., assignors to General Electric Com-
pany, a corporation of New York

Application March 25, 1955, Serial No. 35,208

Term of patent 14 years

(Cl. D44—26)

Fig. 1.

Fig. 2.

Figure 1 is a side elevational view of a coffee maker embodying our new design.

Figure 2 is a top plan view thereof.

Figure 3 is a rear elevational view thereof, the knob portion being shown in partial cross-section.

Figure 4 is a front elevational view thereof.

We claim:

The ornamental design for a coffee maker or similar article, substantially as shown.
